Borger, Tex. 79007

Filed Oct. 23, 1968, Ser. No. 14,138

Term of patent 14 years

Int. Cl. D30—01

U.S. Cl. D30—1

FIGURE 1 is a perspective view of a portable animal enclosure;

FIGURE 2 is a top plan view of the invention;

FIGURE 3 is a side elevation of the invention;

FIGURE 4 is a front elevation of the invention; and

FIGURE 5 is a rear elevation of the invention.

In FIGS. 4 and 5 of the drawings it is to be understood that the broken lines of the roof portion are intended to represent a continuation of the corrugations throughout the areas.

I claim:

The ornamental design for a portable animal enclosure, as shown and described.
